(57) **CLAIM**

The ornamental design for a trailer hitch step, as shown and described.

DESCRIPTION

FIG. 1 is a front view of the trailer hitch step.

FIG. 2 is a back view of the trailer hitch step.

FIG. 3 is a left side view of the trailer hitch step.

FIG. 4 is a right side view of the trailer hitch step.

FIG. 5 is a top view of the trailer hitch step.

FIG. 6 is a bottom view of the trailer hitch step; and,

FIG. 7 is a perspective view of the trailer hitch step from the right corner.

The broken line showing of environment is for illustrative purposes only and forms no part of the claimed design.
